Patented Dec. 20, 1927.

UNITED STATES PATENT OFFICE.

EDWIN ERNEST SPARGO, OF BRUNSWICK, MELBOURNE, VICTORIA, AUSTRALIA.

PROCESS FOR ARTIFICIALLY GRAINING WOOD.

Application filed November 2, 1927, Serial No. 230,636, and in Australia July 2, 1926.

This invention relates to a process of artificially graining or altering the existing grain of wood, for the purpose of imparting thereto grain like figurings or designs, such 5 for example as fiddleback, wavy, mottled or other kinds of figuring or surface ornamentation.

The primary object of the present invention is to provide an improved process for 10 graining or altering the grain of wood, which is simple and inexpensive in practice and enables a wide range of grain like figurings or surface ornamentations to be readily and permanently imparted to the wood. The 15 process according to the present invention is characterized primarily by two steps. The first step consists in subjecting the surface of the wood to the pressure of a die member or members, provided with corrugations, 20 serrations, ridges, projections or the like of any suitable formation whereby the surface of the wood is correspondingly indented, grooved or pitted, whilst the second step consists in subjecting the surface so 25 treated to a planing, buffing, sand papering or such like smoothing operation which is carried on to a depth just sufficient to remove all ridges and the like formed by the die or dies and to leave the surface of the 30 wood perfectly smooth and substantially flush with the bottoms of the grooves and other depressions which were formed therein by the die or dies. The compression of the wood at the bottom of the grooves or the 35 like by the action of the die or dies results in the planed or smoothed surface of the wood being permanently and effectively figured according to the design or grain effect required. The wood may then, if desired, 40 be varnished, stained, French polished or treated with any suitable coating. To render the figuring or surface ornamentation more distinct, the wood may, prior to treatment by the die or die members, be moistened with 45 a solution of carbonate of soda, an aniline dye or any other suitable agent having the desired effect.

When producing fiddleback, wavy, mottled and in fact most kinds of figuring, the 50 grooves, indents and the like formed by the die or die members will extend approximately at right angles across the existing grain markings of the wood which are thus combined with or altered by the artificial markings so as to ensure a perfect imitation of the natural figuring. The improved process may

be readily applied to hard and soft wood and, by the use of appropriately shaped die members, material of square, angle, round, half-round, quarter-round or any other cross section or moulding may be readily treated either over the entire surface or any desired portion thereof.

Referring to the drawings which form part of this specification:—

Figure 1 is a side elevation of an apparatus which may be used for grooving or indenting the wood in accordance with the improved process.

Figure 2 is a view looking in the direction 70 of the arrow in Figure 1.

Figure 3 is a side view of co-operating die members which may be used for grooving or indenting wood of different cross sectional shapes, in accordance with the invention.

Figure 4 is a side elevation of another form of apparatus which may be utilized to groove or indent the wood in accordance with the invention.

According to the apparatus illustrated in 80 Figures 1 and 2, two die members in the form of rollers 6 are mounted in superposed formation in a framework 7 so that the wood 8 may be grooved or indented as it passes between the rollers. Each roller may, if desired, be corrugated or serrated around its periphery as indicated at 9 so that both surfaces of the material may be grooved or indented simultaneously. If it is desired to 90 treat one surface only of the material 8, one of the rollers may be plain or devoid of corrugations and the like.

The corrugations or serrations of the rollers may be of any desired formation according to the figuring or surface ornamentation 95 it is required to impart. The corrugations preferably extend lengthwise of each roller and they may differ one from another in height and in width, and may merge into each other or intersect, if so desired. The rollers may also be provided with projecting knobs or peaks if such are required to produce the figuring or ornamentation.

Each roller 6 may have spindles 11 projecting from its ends, these spindles being 105 accommodated in bearing blocks 12 which may be slidably mounted in guideways 13 formed in each side or end of the frame 7. The bearing blocks for the upper roller may be carried at the lower ends of rods 14 which are connected adjacent their upper 110 ends to arms 16 outstanding from the ends of

a transverse spindle 17 suitably supported by the frame 7. A lever 18 may be connected to and outstand from this spindle, and, if desired, may be provided at its outer end 5 with a weight 19, whereby the upper roller may exert a substantially constant pressure upon the material passing between the rollers irrespective of the thickness of the material. If the material tapers in thickness, 10 the upper roller will rise or fall automatically to accommodate itself to the variations in thickness as the material is fed between the rollers. To permit of vertical adjustment of the upper roller, each of the said rods 15 14 may be provided with a series of vertically spaced holes 21, any one of which may be brought into registry with a hole 22 through the outer end of the adjacent arm 16 so that a pin 23 may be inserted in said co- 20 aligned holes. Instead of the rods 14, arms 16, spindle 17 and associated parts, spring means may be provided to yieldingly force the rollers towards each other so as to exert a substantially constant pressure upon the 25 material passing between them.

A spindle of one of the rollers, preferably of the lower roller, may be provided with an operating handle (not shown) whereby it may be rotated, or, if desired, it may carry 30 a pulley for a power drive.

Before the wood is subjected to grooving or indenting, it may be moistened or impregnated with a solution of carbonate of soda or any other suitable agent which tends 35 to darken the wood, so that when the grooved or indented surface of the wood is subsequently planed or smoothed, the artificial figurings or markings will show with increased clearness. Weak aniline dyes or 40 other solutions may be employed in lieu of carbonate of soda if so desired.

The grooving or indenting may be rendered more efficient by providing for the rollers 6 to be heated during their operation. For this purpose a gas supply pipe 45 26, provided with outlet orifices 27, may extend adjacent each roller 6 so that the flame jets issuing therefrom impinge against the periphery of the respective roller.

The wood may be passed one or more 50 times between the rollers and subsequent to such treatment the grooved or indented surface or surfaces of the material may be planed or sand-papered, or both, to render 55 the same perfectly smooth. This smoothing operation is carried out to sufficient depth to render the new surface substantially flush with the bottoms of the grooves or indents which were formed by the die members. Al- 60 though the surface of the material is thus smoothed the figurings or markings produced by the die members will be clearly visible. The material may now be varnished or polished if so desired.

When dealing with wood of angle, round,

semi-round, and other cross-sectional shapes or mouldings, the rollers 6 may have circumferential channels of appropriate size and shape as indicated in Figure 3. For instance, to impart figuring or surface ornamentation to wood of angle section, one roller may be provided with a circumferential channel 31 of the required cross section, the surfaces of this channel being provided with suitable corrugations, serrations or the like 70 32. The co-operating roller may be plain or devoid of grooves or indentations adjacent the channel 31. For treating material of quarter-round cross-sectional shape, one roller may have a circumferential channel 33 75 of arcuate shape which is provided with corrugations 34 or the like whilst the other roller may have a circumferential channel 36 of angular shape which may be devoid of such corrugations. For treating material of half-round cross-section, one roller may have a circumferential channel 37 of half-round shape which is provided with corrugations or the like 38 whilst the other roller 80 is of normal diameter adjacent the channel 37 and may be devoid of corrugations or the like. For treating material of completely-round cross-section both rollers may be provided with circumferential channels 39 85 of half-round shape, both of which may be provided with corrugations 41 or the like. It will be evident that the rollers may be provided with various forms of circumferential channels for grooving or indenting a 90 surface or surfaces of material of various 95 different cross-sectional shapes.

Although pairs of co-operating rollers have been described, it will be evident that a single roller may be employed in conjunction with a co-operating member of any other suitable form, such for instance as flat or curved plate which may be stationary and may or may not be provided with corrugations, serrations or the like. Furthermore, a corrugated roller may be rolled over 100 the material whilst it is stationary upon a suitable supporting surface.

Instead of utilizing one or more rollers, the die members for grooving or indenting the wood may consist of plates assembled 115 within a suitable press as seen, for example, in Figure 4. In this figure, a die plate 42 may be mounted on the fixed base 43 of the press in alignment beneath a co-operating die plate 44 carried by a presser plate 46 operated by means of a screw 47 which passes through a screwed boss of the frame 48 of the press and is fitted with an operating handle 49 at its upper end. Either or both 120 of these die plates 42, 44, may be provided with any suitable formation of corrugations or the like as indicated at 51, and provision may be made for the rapid interchanging of the die plates. In this embodiment, the wood 125 to be indented or grooved is placed upon the 130

lower die plate 42 and the upper die plate 44 is lowered by manipulation of the handle 49 to subject the material to pressure. The grooved or indented surfaces of the material are subsequently smoothed as before described.

Having now described my invention what I claim as new and desire to secure by Letters Patent is:—

1. A process for imparting grain-like figurings or surface ornamentations to wood, which includes forming grooves under pressure in the surface of the wood which extend transversely of the natural grain thereof, and subsequently smoothing the grooved surface of the wood to thereby remove all ridges or projections and to leave the surface

thereof substantially flush with the bottoms of said grooves.

2. A process for imparting grain-like figurings or surface ornamentations to wood, which consists in moistening the wood, then forming indentations under pressure in the surface of the wood, and subsequently smoothing the indented surface of the wood to thereby remove all surface irregularities and to leave the surface substantially flush with the bottoms of said indentations.

3. A process as claimed in claim 3 wherein the wood is moistened with a solution of carbonate of soda prior to the formation of the indentations.

In testimony whereof I affix my signature.

EDWIN ERNEST SPARGO.
